HAIRPIN

Julius McVicker, Larchmont, N. Y.

Application January 8, 1934, Serial No. 705,671

5 Claims. (Cl. 132—50)

This invention relates to new and useful improvements in hair pins.

The invention has for an object the construction of a hair pin which is adapted to clamp it self upon strands of the hair so as to prevent accidental falling out.

Still further the invention proposes an arrangement whereby the hair pin is provided with portions bent therefrom adapted to do the clamping for maintaining the hair pin in the hair.

Still further it is proposed to so construct the hair pin that the bent portion thereof projects from the hair and constitutes a handle by which the hair pin may be engaged and removed from the hair.

Furthermore as another object of this invention it is proposed to bend certain portions of the hair pin in such a manner so as to more thoroughly and efficiently grip the hair.

As another object of this invention it is also proposed to provide as a modification a hair pin provided with small slideable portions adapted to clamp strands of hair for the purpose of holding the hair pin in the hair.

Still further the invention proposes the construction of an article as mentioned which is simple and durable and which may be manufactured and sold at a reasonable cost.

For further comprehension of the invention, of the objects and advantages thereof, reference will be had to the following description and accompanying drawing, and to the appended claims in which the various novel features of the invention are more particularly set forth.

In the accompanying drawing forming a material part of this disclosure:

Fig. 1 is an elevational view of a hair pin constructed according to this invention.

Fig. 2 illustrates another type of hair pin constructed according to the same form of the invention illustrated in Fig. 1.

Fig. 3 is an elevational view of another hair pin constructed according to another embodiment of this invention.

Fig. 4 is another elevational view of a hair pin constructed according to a still further embodiment of this invention.

Fig. 5 is an end elevational view looking in the direction of the line 5—5 of Fig. 4.

Fig. 6 is another elevational view of a hair pin constructed according to a still further modification of this invention.

Fig. 7 shows a hair pin according to another embodiment of the invention.

Fig. 8 is a sectional view taken on the line 8—8 of Fig. 7.

The hair pin according to this invention comprises a piece of wire bent substantially at the center 10 and having a pair of parallel shank portions 11 all in a common plane. Each of the shank portions 11 has a bent portion near its base forming inward directed points 12 in the said common plane and arranged in such a manner so that the adjacent sides 13 of the points 12 and the inner sides 14 of the shanks 11 are adapted to clamp strands of hair therebetween for the purpose of holding the hair pin from accidentally falling out from the hair. The shanks 11 are shown formed with wavy portions 15, which is conventional construction, for further aiding in holding the hair pin in the hair.

The central bent portion 10 comprises a handle by which the hair pin may be gripped when it is engaged and removed from the hair. The points 12 are formed by bending the portions 16 of the wire rearwards and the shanks 15 are continuations from the portions 16 but extend towards the front. The hair pin is used in a conventional manner except for the fact that when engaged into the hair some of the strands will naturally engage between the adjacent surfaces 13 and 14 of the points 12 and the shanks 15 and so tend to hold the hair pin from coming out. The points 12 are adapted to easily engage in among the hairs so as to guide some of the strands between the clamping surfaces. The hair pin may be withdrawn by gripping the handle portion 10 and pulling upon it to cause the strands clamped as before explained, to disengage.

In Fig. 2 another hair pin has been disclosed which is identical to the arrangement shown in Fig. 1 except for the fact that it is provided with shank portions 11' of straight construction contrasted with the previous arrangement where the shanks have the wavy portion 15. In other respects this hair pin is identical to that previously described and similar parts may be recognized by the same reference numerals.

In Fig. 3 another type of hair pin has been shown embodying the same principle of this invention and distinguishing from the previous form merely in the fact that it is provided with rearward bent portions 16' twisted to form strand gripping points 17 and also handle portions in conjunction with the handle portion 10. The shanks 11 extend from the twisted portions 16'. In other respects this form of the invention is identical to that previously described and similar parts may be recognized by the correspond-

ing reference numerals. The distinction of this form resides in the fact that the strands of hair entering between the surfaces 13 and 14 will have a tendency to engage into the seam of the twist at the points 17 of the twisted portion and so insure a greater gripping action. The rear portions of the twisted portions 16' may also be used as handles for better gripping the hair pin.

10 In Figs. 4 and 5 another embodiment of the invention has been disclosed wherein there are rearward bent portions 16^a from the points 12 and being bent out of the common plane of the remaining portion of the wire comprising 15 the hair pin. More particularly one of the portions 16^a is bent outwards and the other upwards as clearly illustrated in Fig. 5. In other respects this form of hair pin is identical to the form described in Fig. 1 and similar parts may 20 be recognized by corresponding reference numerals. The feature of this hair pin resides in the fact that in addition to strands of hair being clamped between the gripping surfaces 13 and 14, one or the other of the portions 16^a bent 25 out of the plane of the hair pin will engage at right angles into the hair and so tend to aid in holding the hair pin from coming out of the hair. A feature is that irrespective of the manner in which the hair pin is engaged in the 30 hair either one or the other of the bent portions 16^a will be directed towards the head and so engage the hair.

In Fig. 6 another modified form of the invention has been disclosed wherein each of the 35 shanks are provided with oppositely directed pointed portions functioning to produce oppositely directed gripping points to better prevent the hair pin from disengaging from the hair. More particularly this hair pin comprises a central bent portion 10 of substantially U-shape 40 from which there are rearward bent portions 16 forming the points 12. The shanks 11 are continuations from the rearward bent portions 16 but these shanks are provided with rearward bent 45 portions 19 arranged to terminate a slight distance from the points 12 as clearly illustrated on the drawing. With this arrangement there are clamping points between the sides 13 of the points 12 and the inner sides 14 of the shank. 50 Still further there are other clamping points between the inner sides 20 of the pointed portions 19 and the inner sides 14 of the shanks. The arrangement is such that when the hair pin is engaged inwards into the hair the rearward bent portion 19 will tend to guide the hair against the inner side 13 of the points 12 and these sides 13 will guide the hair inwards into the 55 area between the points 12 and 19. The strands entering this area will be clamped in the points 19 and the inner sides 14 of the shanks. The arrangement is such that when the hair pin is engaged inwards into the hair the rearward bent portion 19 will tend to guide the hair against the inner side 13 of the points 12 and these sides 13 will guide the hair inwards into the area between the points 12 and 19. The strands 60 entering this area will be clamped in the points 19 and the inner sides 14 of the shanks. Other of the strands entering this area will be clamped in the points between the sides 14 and 20, particularly should the hair pins have a tendency to move outwards. It is obvious that with this arrangement the hair pins once engaged properly in the hair cannot possibly accidentally fall from their positions. To remove the hair pins it is necessary that the strands of hair be guided 65 out from between the points 19 or 12 or it is necessary that the strands of hair be pulled through the area so that the free ends of the strands actually pass out from this confining area.

In Figs. 7 and 8 another modified form of the 70 invention has been disclosed wherein a hair pin is shown comprising a central bent portion 10

constituting a handle for the hair pin and continuations from the bent portion comprising parallel shank portions 11. These shank portions are in a common plane with the bent portion 10. Near the bases of the shank portions 11 there are rearward bent portions 19 also in the same common planes arranged to have inner sides 20 adapted to clamp hair in conjunction with the inner sides 14 of the shank. In addition to supplement the clamping action small fingers 22 project from collars 23 slidably arranged upon the arms of the U-shaped bend 10. An arrangement is provided to prevent rotation of these fingers and comprises flattening portions 24 against which the sides of the clamps 23 engage. 15 These clamps are adapted to frictionally engage the flattened sides 14 so as to maintain in set portion of longitudinal adjustment. When this hair pin is engaged in the hair certain of the strands will be guided into the area between the fingers 22 and the rearward bent portions 19 and certain of these strands will be clamped between the inner surfaces 25 of the fingers 22 and the inner surfaces 26 of the collars 23. Other of these strands will be clamped between the sides 25 14 and 20. With this form of hair pin the hair may be disengaged by sliding the fingers 22 sufficiently rearwards so that all of the strands which are clamped may be released.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:—

1. A hair pin, comprising a piece of wire bent substantially in the center and having a pair of parallel shank portions in a common plane, and each shank portion associated with a portion near the base including inward directed points in said common plane and the adjacent sides of said shanks and point portions being adapted to clamp strands of hair for the purpose of holding the hair pin from accidentally falling out.

2. A hair pin, comprising a central U-shaped portion constituting a handle, rearward bent portions from the ends thereof and extending up and down out of the plane of said handle and forward continuations from said rear bent portions in the same plane as said U-shaped portion comprising a pair of parallel shank portions for the hair pin.

3. A hair pin, comprising a central U-shaped portion constituting a handle rearward bent portions from the ends thereof and extending up and down out of the plane of said handle, and forward continuations from said rear bent portions in the same plane as said U-shaped portion comprising a pair of parallel shank portions for the hair pin, the adjacent sides of the rearward bent portions and the shanks being adapted to clamp strands of hair for the purpose of holding the hair pin from accidentally falling out of the hair, and one or the other of said portions bent out of the common plane being adapted to engage into the hair for further holding the hair pins from displacement.

4. A hair pin, comprising a piece of wire bent substantially in the center and having a pair of parallel shank portions in a common plane, and

each shank portion associated with a portion near the base thereof forming inward directed points in said common plane and the adjacent sides of said shanks and point portions being 5 adapted to clamp strands of hair for the purpose of holding the hair pin from accidentally falling out, said shank portions also being provided with rearward extending angular portions opposed to said pointed portions for guiding strands of hair 10 within the area divided off by these parts and also to provide additional clamping portions for the air located between the adjacent sides of said

upward angular portions and the rear sides of said shank portions.

5. A hair pin, comprising a U-shaped central portion with a pair of parallel shank continuations, each of said shank continuations being provided with rearward bent angular portions near the base thereof, and fingers slidably arranged upon the shanks and extended in the same plane as said shanks and rearward angular portions, and adapted to clamp hair substantially 10 as described.

JULIUS McVICKER.
